CLAIM

The ornamental design for an underarm support of a crutch, as shown and described.

DESCRIPTION

FIG. 1 is a top perspective view of an underarm support of a crutch in accordance with the present design;

FIG. 2 is a bottom perspective view thereof;

FIG. 3 is a left side view thereof;

FIG. 4 is a right side view thereof;

FIG. 5 is a rear view thereof;

FIG. 6 is a front view thereof;

FIG. 7 is a top view thereof; and,

FIG. 8 is a bottom view thereof.

The broken lines shown in the drawings illustrate portions of the underarm support of a crutch that form no part of the claimed design.

1 Claim, 6 Drawing Sheets
